UNITED STATES PATENT OFFICE

2,270,981

FOLDING SEAT

John H. Tuttle, Kalamazoo, Mich., assignor
to Checker Cab Manufacturing Corporation,
Kalamazoo, Mich.

Application January 27, 1940, Serial No. 315,875

1 Claim. (Cl. 155—12)

This invention relates to folding seats for automobiles of the type ordinarily employed in taxicabs forwardly of the rear seat to increase the passenger carrying capacity of the cab. It has for its objects:

First, to produce a new and improved chair of the class above mentioned.

Second, to provide such a chair which is simple in construction and which can be made inexpensively.

Third, to provide such a chair with a positive stop to hold the chair against backward movement when the chair is in use.

Fourth, to provide such a chair with a stop mechanism which is wholly concealed and which does not project above the floor of the vehicle.

Fifth, to provide such a chair which in folded position projects above the floor of the vehicle a minimum amount.

Sixth, to provide in such a chair a new and improved stop for the folding back.

Seventh, to provide such a stop which will not pinch or catch the clothing or fingers of the occupants of the cab when the chair is moved from lowered to raised position.

Other objects and advantages pertaining to details and economies of construction and operation will appear from the description to follow. The invention is defined in the claims. A preferred embodiment of my invention is illustrated in the accompanying drawing, in which:

Fig. 1 is a view in section on line 1—1 of Fig. 3, showing my improved chair.

Fig. 2 is a perspective view showing the chair in folded position.

Fig. 3 is a detail sectional view taken on line 3—3 of Fig. 1.

Fig. 4 is a detail view in section showing the stop for the chair back.

My new and improved chair 1 consists of a frame 2, a seat 3, back 4 pivoted to the frame at 5, and front legs 6.

To connect the chair to the floor 7 of the vehicle, I provide a pair of plates 8 apertured at 9 and adapted to be located adjacent apertures 10 in the floor 7 and with the openings 9 and 10 in register. The floor is countersunk at 11 to receive the plate 8 which is fastened by suitable bolts 12 to the floor 7 and the supporting frame members 13.

The legs 6 are of spring steel of round cross section. The lower ends of the legs extend through the apertures 9 and 10 and are bent forwardly as at 14 at substantially a right angle. The legs are hinged on a pintle 15 located at the

forward portion of the bend in the leg to the front edge 16 of the plate 8 by means of the hinge member 17 which is riveted with rivets 18 to the forwardly bent portion of the legs. The pintle extends through suitable bearings 19 in the plate 8.

On the floor of the vehicle, I provide a suitable rubber pad 20 which is apertured at 21 for the passage of the legs 6 and has a recess 22 extending forwardly from the point of connection between the legs 6 and the floor 7 of the vehicle to receive the forward portion of the legs 6.

The back 4 of the chair is hinged on a pintle 5 which extends between ears 23 in a slot 24 which receives the ear 25 on the back. A stop 26 is formed between the ears 23 to engage a stop 27 on the ear 25. The pintle 5 is located forwardly of the slot 24 and the stop 27 is of such length that when the chair seat is raised and the back 4 is raised to the position shown in Fig. 1, the stop 27 lies between the ears 23 in the slot 24.

When my chair is in the lowered position shown in Fig. 2, the stop which holds the chair against backward movement when the chair is in use is completely concealed below the floor 7 of the car and does not present an obstacle to the ingress and egress of passengers. The legs 6 lie in the recesses 22 with only their rounded backs projecting above the recesses causing a minimum of obstruction.

When the chair is moved to raised position, as shown in Fig. 1, the forwardly bent ends 14 of the legs engage the bottom of the plate 8 providing a very positive concealed stop.

The stop 27, being wholly protected by the ears 23 in the slot 24, will not pinch or catch the clothing or fingers of occupants of the cab when the back is raised.

It will be perceived that the above described structure when installed is completely free from the presence of recesses or other depressions in the vehicle floor in which dust, dirt, debris and the like are apt to accumulate. Such accumulation, if not removed, and the removal thereof is usually inconvenient, would ordinarily prevent full collapsing of the legs to inoperative position.

The terms and expressions which have been herein employed are used as terms of description and not of limitation. There is no intention in the use of such terms and expressions of excluding any equivalents of the features shown and described or portions thereof. It is recognized that various modifications are possible within the scope of the invention claimed.

Having thus described my invention, what I

claim as new and desire to secure by Letters Patent is:

In a chair of the class described, the combination of a pair of apertured plates adapted to be disposed at apertures of relatively limited front to rear length in the floor of a vehicle each with its aperture in register with one of said apertures in said floor, a pair of front legs each having its lower end extending through the aperture in one of said plates and bent forwardly at substan-

tially a right angle to engage the bottom of said plate when the chair is in raised position, said legs being hinged at the forward portion of the bend thereof to the front edge of the aperture of said plate, the portion of said legs above the bend therein being disposed over the floor forwardly of the aperture therein and adapted to rest thereon in lowered position of the chair.
